TOY BOAT

Victor Goldberg and Max L. Goldberg,
Baltimore, Md.Application November 28, 1932
Serial No. 644,730

21 Claims. (Cl. 46—37)

This invention relates to toy boats and more particularly to paper boats.

It is an object of this invention to form from an initially flat blank of paper a boat that is 5 impervious to water and which furthermore is capable of being floated.

Another object of this invention is to provide a specially designed blank from which the boat is to be made, having imprinted thereon, on 10 each side thereof, a plurality of consecutively numbered lines each of a predetermined length, to indicate where the folds are to be made and which certain of said lines will appear as the folding progresses to indicate where the next sequential folds are to be made.

A still further object of this invention is to combine with the boat, an insert which is adapted to be placed within and attached to the boat, which insert is to represent pictorially the 20 superstructure of a vessel, that is;—the sails, masts, cabins of a sail boat or if desired the stack, towers, cabins of a steamboat, in fact the superstructure of any selected kind of craft.

Another object of this invention is to form 25 this boat from a pre-designed blank by a folding process which involves a definite series of simple folds without any necessary cutting, fitting and the securing together of a plurality of parts as heretofore required in the making of 30 toy boats.

The paper boat described hereinbelow and the method of forming the same is clearly shown in the accompanying drawings, in which:—

Fig. 1 is a perspective view of the boat in its 35 entirety, and Fig. 1^a is an end elevation thereof.

Fig. 2 is an elevational view of one part of the insert.

Fig. 3 is an elevational view of the other part 40 of said insert.

Fig. 4 is a plan view of the upper side or top of the blank from which the boat is made.

Fig. 5 is a plan view of the bottom side of 45 said blank.

Figs. 6 to 25 inclusive, show in succession, respectively, the various steps in folding the blank to form the boat.

Referring to the complete showing of the boat in Fig. 1, A designates the hull of the boat, which comprises fore and aft decks *a* and *b* 50 spaced apart as shown, each having a pair of outwardly converging sides and a pair of inwardly converging sides. Both the decks *a* and *b* are substantially flat and are in the shape of a quadrilateral the long diagonal of which 55 coincides with the longitudinal axis of the boat.

Extending between the corners *c* of the decks *a*, *b* are laterally inclined sides *d* which converge to a keel *e*, the upper edges of said sides *d* being parallel to each other and in the same plane. Beneath each of the decks *a*, *b* are parallel 60 spaced vertical sides or walls *f* and *g* which are in the same plane with the longitudinal axis of the boat and support said decks connecting the same with the keel *e*, the outer edges of each of said vertical sides being joined together and 65 inclined downwardly from the outermost corners or juncture of the outwardly converging sides of the decks to the ends of the keel.

On each side of each of the vertical sides *f* and *g* and connecting the same as well as the 70 decks *a*, *b* with the ends of the inclined sides *d* are transverse substantially vertical walls or sides *h* more clearly shown in Fig. 1^a. Projecting from the medial horizontal center of the inclined sides *d* are downwardly extending fins 75 or flaps *i* which function to maintain the boat on an even keel when the same is floating or to maintain the toy boat in an upright position when the same is placed on a flat surface as for example a table top, indicated by the line *j*—*j* 80 in Fig. 1^a. Formed integral with the outer converging sides or edges of the decks *a*, *b* are vertical upwardly projecting railing walls *k* which at their juncture define with the inclined edges of the vertical sides *f*, *g* the prow and stern of the 85 boat as clearly shown.

Located between the decks *a* and *b* is an open hatch *m* the side walls *n* of which are vertically spaced from the inclined sides *d* but which however join said sides *d* at the keel *e*. The end 90 walls *p* of the hatch *m* are integral with the inner corners of the decks *a*, *b* as at *r* and are similarly spaced from the transverse walls *h*. Dividing each of the decks *a*, *b* along their longitudinal axis is a vertical slot *s* which extends from the surface of the decks *a*, *b* to the bottom of the keel *e*, separating the vertical sides *f*, *g* as well as the transverse walls *h*, as most clearly shown in Fig. 25.

The above defined portions of the boat A are 100 all integral and are formed from a single blank in the manner to be hereinafter set forth.

Adapted to be securely positioned within each of the slots *s* is an insert *t* which is preferably made of a stiff cardboard or any other suitable 105 material and shaped at its upper part *t*¹ to represent as shown in Fig. 1 part of the superstructure of a sailing vessel. The lower portion *t*² of the insert *t* is shaped to closely fit the entire space defined by said slots, the shape of the lower 110

part being in fact determined by the outline of the boat at its longitudinal medial portion as clearly shown in Fig. 2. Formed in the insert *t* is a vertical slot *t*³ that extends from the bottom thereof to a point spaced from the top, the purpose of this slot to be hereinafter described. Preferably this slot is made adjacent the printed outline of the mast *t*⁴, Fig. 2. An additional insert *u* of like material is also provided and compromises an upper portion *u*¹, Fig. 3, shaped to represent the sails and mast of a sailing vessel and a lower portion *u*² so shaped as to snugly fit transversely within the hatch *m*, the inclined edges of said lower portion engaging the inner adjacent side walls of the hatch. The upper part of the insert *u* is provided with a short slot *u*³ which is on the longitudinal axis of said insert. The slot *t*³ in the insert *t* and the slot *u*³ in the insert *u* are each of a width substantially equal to the thickness of said inserts, the insert *u* being adapted to be slid transversely into the slot *t*³ of the insert *t*, the slot *u*³ receiving therein the unslootted upper portion of the insert *t*.
 25 The inserts *t* and *u* being thus connected, they are then inserted into the boat, the insert *t* fitting within the slots *s* and the insert *u* within the hatch *m* and in engagement with the adjacent end walls *p* of the hatch. When so inserted the inserts *t* and *u* are securely held within the boat, the insert *u* being thus maintained at all times at right angles to the insert *t*.

If desired both the inserts *t* and *u* may be provided with adhesive zones *w*, Figs. 2 and 3, on each side of the lower parts *t*² and *u*² respectively, which zones are adapted to be moistened prior to the insertion of the inserts into the boat, whereby the same may be positively secured to the boat proper.

40 The longitudinal insert *t* may have formed at the front end thereof an extension *t*⁵ adapted to project over the prow of the boat said extension having an opening *t*⁶ therein, whereby a string may be attached thereto for pulling the boat when the same is floating on water.

It is to be understood that the form of insert above described is merely an example of one definite type, that said insert may be made to depict the superstructure of any type of vessel, 50 and that if desired the longitudinal insert such as *t* or the transverse insert such as *u* may be used either singly or in combination, all depending on the type of vessel superstructure selected. In any event, irrespective of the type 55 of insert used the lower parts thereof such as *t*²—*u*² will always be the same. The longitudinal insert *t*, may if so desired, be replaced by two single inserts each to fit within a slot *s*.

As heretofore pointed out the above described 60 boat is formed from an initially flat blank. Such a blank is shown in Figs. 4 and 5 and comprises a blank of paper or any other suitable material, rendered moisture proof if desired, of comparatively strong texture and stiffness, yet 65 capable of being readily folded. The blank *B* is a square in form and has ruled or printed on each side thereof a plurality of lines, each bearing a definite relation to the other and each of a predetermined length, the lines on one side 70 of the blank being also definitely located with respect to the lines on the other side of the blank. These lines indicate on the blank where and in what sequence the necessary folds are to be made to form the boat in the manner now 75 hereinafter set forth.

Starting with the blank, having the top side, Fig. 4, facing upwardly, folds are made along the lines 1, bringing each of the four corners of the blank to the center of the top side of the square as shown in Fig. 6. The blank is then folded along the lines 2—2, bringing the outer edges thereof parallel with said lines together, as in Fig. 7. Next, folds are made on lines 3—3, bringing the other edges of said blank parallel to said latter lines, together, as in Fig. 8, then by reversing the blank, a fold is made along the line 4. The folded blank will now be in the form shown in Fig. 10.

Maintaining the folded blank at this stage in the position shown in Fig. 10, and by moving each of the outer upright portions *v* partly away from the intermediate portion *w*¹, folds are made along each of the diagonal lines 5, Fig. 11, there being two such lines on each side of said intermediate portion. Referring to Fig. 11, it will be observed that the single fold illustrated therein, extends merely along the diagonal line 5 from the upper center of the intermediate portion *w*¹ to the lower (right) corner thereof. Upon the completion of each of these four folds along the 100 lines 5, the upright outer portions *v* are brought intimately together, the folded blank then assuming the form shown in Fig. 12.

The next step in the formation of the boat is to again separate the outer portions *v* as 105 shown in Fig. 13 and to pull completely out of the folded blank the flaps *x*, there being one on each side of the intermediate portion *w*¹. Shown in dotted lines in Fig. 13, in complete unfolded position are one of the flaps *x*. Upon 110 the removal of each of the flaps *x* the outer portions *v*—*v* are again brought intimately together. The folded blank at this stage assuming in elevation the form shown in Fig. 14.

On each side of the folded blank shown in 115 Fig. 14 appear the lines 6—6—6, and upon folding along each of said lines on each side of the blank, each of the outer corners will be brought substantially together at the center of the square defined by the lines 6—6—6 and the 120 bottom of the blank, the blank then taking the form shown in elevation in Fig. 15. It is understood that similar operations as above set forth are performed upon each side of the folded blank of Fig. 14, with the consequent formation 125 of identical details on each side of the form taken by the blank in Fig. 15. The blank at this stage comprises lower rectangular portions *y* connected together, and upper separate rectangular portions *y*¹, which are in the next step 130 each folded over the adjacent lower portions *y*, the folded blank in its natural or relaxed position at this stage having the formation shown in Fig. 16, and which subsequently takes a box like form shown in Fig. 17, upon the opening up 135 of the folded blank, Fig. 16, by merely an "accordion" like outward movement of the sides *y*², Fig. 16.

On the outside of each of the longitudinal sides *z*, of the box in Fig. 17, is a line 7 that 140 is positioned in the longitudinal center of said sides, the ends of said lines terminating short of the ends of said sides as clearly shown. The next folds are made along these lines 7, in such a manner as to bring the upper and lower edges 145 of each of said sides into close contact whereby the box, Fig. 17, will upon the completion of said folds, take the form shown in perspective in Fig. 18. The vertical walls *z*¹ are now folded inwardly in the direction of the arrows, on the 150

lines 8 appearing on the reverse side of the folded form Fig. 18, to contact said reverse side as shown in Fig. 19. Fig. 20 is a view of the reverse side of the folded form shown in Fig. 19, disclosing the line 9—9 upon which the next fold is made. Upon the completion of this fold the blank will have the folded form shown in Fig. 21.

The next sequential operation in the formation of the boat is to hold the center portion of the folded form of Fig. 21 indicated by the triangular flaps or fins *i* and to pull outwardly and upwardly in the direction indicated by the arrows each of the lower corners of the folded form. This operation will cause the folded form of Fig. 21 to eventuate into the hull of the boat as shown in Fig. 22. Following this operation there is next pulled outwardly and upwardly each of the portions *a*¹, part of the same being folded within the slots *s*, the remaining being superposed over the decks *a*, *b*. The portions *a*¹ will upon being pulled out from vertical converging walls as shown in Fig. 23, which at their juncture define the prow and the stern of the boat.

On the inside of each of the wall portions *a*¹ appear diagonal lines 10 which extend downwardly from the upper corner of the juncture of said walls to the outer corners of the decks *a*, *b*. Folds are then made inwardly along each of the lines 10, the wall portions *a*¹ then taking the form shown, *a*², in Fig. 24. Again on the inside of the walls *a*² appear lines 11 which are parallel to the surface of the decks *a*, *b* and which are spaced midway between the top and bottom of the walls *a*², along which lines the next folds are accordingly made by bending the upper portion of the walls *a*² inwardly along said lines down into engagement with the lower inside portions of said walls, thus taking the form shown in Fig. 25 wherein said folded walls take the finished form of the railing walls *k* shown also in Fig. 1.

While the preferred form of the complete hull of the boat is that shown in Fig. 25, it is to be understood that the forms shown in either Figs. 22, 23 or 24 may also be used as the complete hull in combination with the inserts as above indicated. Furthermore either of the forms shown in Figs. 22, 23, 24 and 25 may be used, if so desired, without the addition of inserts thereto.

It is to be further understood that various changes may be made in the construction and the arrangement of the boat and the inserts without departing from the spirit of the invention or the scope of the claims.

We claim:—

1. A toy boat comprising fore and aft decks, laterally inclined sides between said decks terminating in a keel, vertical sides beneath each of said decks and in the same plane with the longitudinal axis of said boat, transverse walls connecting said decks and vertical sides with said laterally inclined sides, a longitudinal separable insert positioned between said vertical sides, and a transverse separable insert interconnected with said longitudinal insert and positioned adjacent said transverse walls.

2. A toy boat comprising spaced fore and aft decks each having outwardly converging sides, laterally inclined sides between said decks terminating in a keel, vertical sides beneath said decks, transverse walls connecting said decks, and vertical sides to said laterally inclined sides,

vertical railing walls projecting from the converging sides of said decks and at their juncture defining the prow and stern of said boat, and a longitudinal separable insert positioned between said vertical sides the end edges thereof engaging the juncture of said railing walls, whereby said insert is locked against longitudinal movement.

3. The structure specified in claim 2, said vertical sides, keel, juncture of said fore and aft railing walls and insert being in the same vertical plane.

4. A toy boat comprising fore and aft decks, laterally inclined sides between said decks terminating in a keel, vertical sides beneath each of said decks and in the same plane with said keel, transverse walls connecting said decks and vertical sides to said laterally inclined sides, a hatch between said decks, railing walls joined to said decks, an outwardly projecting fin extending from each of said laterally inclined sides, a longitudinal separable insert positioned between said vertical sides, and a transverse separable insert positioned in said hatch, and means for locking said inserts individually to said boat.

5. A toy boat formed as an integral unit from an initially flat blank of foldable material comprising fore and aft decks provided with outwardly converging sides, laterally inclined sides between said decks terminating in a keel, vertical sides beneath said decks, transverse walls connecting said decks and vertical sides to said laterally inclined sides, railing walls connected to the outwardly converging sides of said decks and at their juncture defining the prow and stern of said boat, each of said vertical sides having an outer edge inclined from said prow and stern to the ends of said keel and in the same plane therewith, a longitudinal separable insert positioned between said vertical sides and provided with inclined ends engaging the inclined outer edges of said vertical sides.

6. A toy boat comprising fore and aft decks, laterally inclined sides between said decks terminating in a keel, vertical sides beneath each of said decks and in the same plane with said keel, transverse walls connecting said decks and vertical sides to said laterally inclined sides, railing walls joined to said decks, a separable flat insert having the characteristics of the superstructure of a boat attached to said boat, and provided with an underportion fitted within said boat to engage the keel and vertical sides and adapted to be locked therewith against movement relative thereto.

7. A toy boat comprising fore and aft decks, laterally inclined sides between said decks terminating in a keel, vertical sides beneath each of said decks and in the same plane with the longitudinal axis of said boat, and transverse walls connecting said decks and vertical sides with said laterally inclined sides, a hatch between said decks and a plurality of flat interlocking separable inserts having the characteristics of the superstructure of a boat arranged in intersecting planes and attached to said boat.

8. In a toy boat, spaced decks at each end thereof, an open hatch between said decks, a longitudinal slot in each deck, said slots being in the same plane with the longitudinal axis of said boat, and a plurality of flat interlocking separable inserts having the characteristics of the superstructure of a boat arranged in intersecting planes, one of said inserts being adapted

- to fit within said longitudinal slots and at least one of said other inserts being connected with said first mentioned insert and adapted to fit within said hatch.
5. 9. In a toy boat, spaced decks at each end thereof, an open hatch between said decks, a longitudinal slot in each deck, said slots being in the same plane with the longitudinal axis of said boat, and a plurality of inserts having 80 the characteristics of the superstructure of a boat arranged in intersecting planes, one of said inserts being adapted to fit within said longitudinal slots and at least one of said other inserts being connected with said first mentioned insert and adapted to fit within said hatch, and means on said inserts for positively securing the same to said boat.
10. 10. In a toy boat, a deck, spaced walls arranged within the boundaries thereof and joined beneath said deck, a keel, and a separable flat insert having the characteristics of the superstructure of a boat provided with a flat underportion adapted to be positioned between said walls, the side and bottom edges of said underportion engaging respectively the joined portions of said walls and said keel. 85
15. 11. In a toy boat, spaced decks, spaced walls arranged within the boundaries of each of said decks, and a separable flat insert having the characteristics of the superstructure of a boat positioned between the spaced walls in at least one of said decks, and means on said insert for securing the same to each of said walls. 90
20. 12. In a toy boat, a deck, parallel supporting walls arranged between the side edges thereof and joined beneath said deck, said walls adapted to receive therebetween an insert having the characteristics of the superstructure of a boat, said insert having a flat underportion 95 conforming in shape to said parallel walls and means on said underportion for securing the same to said wall.
25. 13. In a toy boat comprising a hull, a detachable insert having the characteristics of the superstructure of a boat provided with a flat underportion, means on said hull adapted to intimately receive said flat underportion, and means on said insert for locking the same to said hull. 100
30. 14. In a toy boat comprising a hull, a plurality of detachable inserts having the characteristics of the superstructure of a boat separably arranged in intersecting planes, each of said inserts being provided with flat underportions, means on said hull adapted to intimately receive said flat underportions, and means on at least one of said inserts for locking the same to said hull. 105
35. 15. In a toy boat, a hull formed as an integral unit from an initially flat blank of foldable material, a detachable insert having the characteristics of the superstructure of a boat provided with a flat underportion, means on said hull adapted to intimately receive said flat underportion, and means on said insert for locking the same to said hull. 110
40. 16. In a toy boat, a hull formed as an integral unit from an initially flat blank of foldable material having non-intersecting directional fold lines of definite length inscribed on each side thereof and definitely positioned with respect to each other to indicate where and in what sequence the folds are to be made, a detachable insert having the characteristics of the superstructure of a boat provided with a flat underportion, means on said hull adapted to intimately receive said flat underportion, and means on said insert for locking the same to said hull. 115
45. 17. A separable composite insert for a toy boat having the characteristics of the superstructure of a boat comprising separate members arranged in intersecting planes, one of said members being provided with a slot extending upwardly from the bottom edge thereof, the other member being provided with a similar slot extending downwardly from the upper edge thereof, the members being so arranged that the slot of one member will receive therein a portion of the body of the other member, whereby said members are interlocked with respect to each other. 120
50. 18. The structure specified in claim 17, and means on each of said members for attaching the same to the hull of a toy boat. 125
55. 19. A separable composite insert for a toy boat comprising separate members arranged in intersecting planes, each of said members being flat and provided with an upper portion having the characteristics of the superstructure of a boat and a lower portion, a slot in each of said members, the members being so arranged that the slot of one member will receive a portion of the body of the other member so as to interlock one member with respect to the other. 130
60. 20. The structure specified in claim 19, and means comprising adhesive zones on the lower portion of at least one of said members for securing said insert to said toy boat. 135
65. 21. The structure specified in claim 19, one of said members being adapted for mounting on said toy boat along the longitudinal axis thereof, and means forming a part of said member projecting beyond at least one of the ends of said boat. 140
